ROTARY COMPRESSOR OR SUPERCHARGER

Erling Borsting, Mount Vernon, Ohio

Application April 19, 1943, Serial No. 483,589

2 Claims. (Cl. 230—152)

1

My invention relates to a rotary compressor or supercharger. It has to do particularly with a reversible compressor or supercharger adapted to use as a scavenging blower for two-cycle internal combustion engines, although its use is not necessarily so limited since it is equally well adapted for use as a supercharger for two-cycle or four-cycle engines, as well as a rotary pump for liquids, such, for example, as oil.

The reciprocating type of scavenging blowers of the prior art which are used on two-cycle engines are directly reversible and therefore are suitable for reversible engines. This type of blower is necessarily very large and therefore not suitable for use with high speed engines. Heretofore, high speed engines have used some form of rotary compressors or blowers, usually the Roots type.

Rotary compressors or blowers are not reversible for the reason that if their direction of rotation is reversed the air flow is also reversed and therefore the blower could not be used with a reversible engine because the air must always be pumped or forced into the engine. Such blowers have thus necessarily been equipped with reversing valves of large size because of the large volume of air which the blower had to handle. Reversing gears have also been employed but such gears add materially to the cost and substantially increase the size of the unit. Therefore, there is a distinct need for a directly reversible rotary compressor for use with reversible high speed engines, particularly marine engines.

My present invention makes it possible to reverse the sliding vane type of rotary compressor without materially increasing the size of the unit. The sliding vane type of rotary compressor can be made to compress the air before discharge which makes for high efficiency and quietness of operation.

One of the objects of my invention is to provide an improved rotary compressor, blower, or supercharger which is capable of being driven in either direction.

Another object is to provide an improved compressor, blower, or supercharger which, regardless of the direction of rotation of the rotor or impeller thereof, will always draw in the fluid, such as air, through the intake opening, compress it, and discharge it through the exhaust opening.

Another object is to provide an improved compressor of the foregoing character which automatically reverses its direction of rotation upon

2

the reversal of rotation of the power plant or other instrumentality to which it is connected.

Generally speaking, the compressor, blower or supercharger embodying my invention, as shown, consists of a housing or casing, one side thereof having an intake opening and the other side an exhaust or discharge opening. A drive shaft is mounted in suitable bearings carried by hangers located within the housing and carries a rotor 10 provided with a plurality of preferably lined pockets in which slideable vanes or blades are located. The shaft and the rotor are arranged eccentrically within the housing. Interposed between the housing and the rotor is a cylindrical member 15 or cylinder having a plurality of ports formed therein and with which the vanes cooperate to compress the air or other fluid entering through the intake opening. The ports in the cylinder are adapted to align or register with the intake 20 and exhaust openings and since the cylinder is free to be rotated automatically through approximately 180 degrees at predetermined times, it will be seen that different ports therein align or register with the intake and exhaust openings dependent upon the position of the cylinder with 25 relation to the housing. Regardless of the position of the cylinder, however, the air is always admitted through the intake opening and discharged through the exhaust opening of the 30 housing.

The exhaust side of the housing is provided with a plurality of longitudinally spaced ribs which align with and at certain times cover some of the ports in the cylinder so as to always discharge the compressed air through the exhaust opening in the housing regardless of the direction of rotation of the rotor.

To reduce friction and consequent wear and overheating, the vanes of the rotor are maintained out of direct contact with the wall of the cylinder. For this purpose I preferably provide the opposite ends of the vanes with notched-out portions which support rockable bearing blocks which may be made from some suitable self-lubricating metal. These blocks engage floating rings at opposite ends of the rotor and the rings are free to rotate on suitable bearings. Due to the contact of bearing blocks carried by the end portions of the blades with the rings, these rings are forced to rotate although there will be some slippage and the rings and the rotor will not operate at the same speeds. The net results of this will be that only a small fraction of slippage will occur as compared to the amount of slippage which would result from the use of a stationary

ring or rings. The free edges of the vanes are maintained spaced slightly away from the cylinder wall.

If it should appear to be desirable to prevent leakage of the indrawn air or other fluid, I may provide each of the rotor vanes with a strip-like member or piece of some suitable material such, for example, as fiber, hard rubber, Bakelite or other suitable material. These members engage the inner wall of the cylinder and upon operation of the rotor, wear themselves in so as to follow the contour of said inner wall.

The invention, therefore, comprises a relatively small, compact and simply constructed reversible rotary compressor, blower or supercharger in which friction is reduced to a minimum by virtue of my improved manner of lubrication of the parts. Due to the reduction of friction and the proper lubrication of the parts, there is virtually no wear, thus the life of the unit is greatly prolonged. These features having to do with the support of the vanes and the lubrication, would apply equally well if the compressor were capable of operation in one direction only.

The above and other objects and advantages will appear from the following description and appended claims when considered in connection with the accompanying drawings forming a part of this specification wherein like reference characters designate corresponding parts in the several views.

In said drawings:

Figure 1 is a vertical longitudinal sectional view through my improved rotary compressor or supercharger, taken substantially along the line 1—1 of Figure 2, looking in the direction of the arrows.

Figure 2 is a transverse vertical sectional view taken substantially along the line 2—2 of Figure 1, looking in the direction of the arrows.

Figure 3 is a view similar to Figure 2 and showing the rotor in a position opposite to that in which it is shown in Figure 2.

Figure 4 is a horizontal longitudinal sectional view, partly in elevation and partly broken away, of the rotary compressor or supercharger of the preceding views.

Figure 5 is a vertical sectional view of the drive gearing taken substantially along the line 5—5 of Figure 4, looking in the direction of the arrows.

Figure 6 is a vertical section taken substantially along the line 6—6 of Figure 4, looking in the direction of the arrows.

Fig. 7 is a vertical sectional view taken substantially along the line 7—7 of Figure 4, looking in the direction of the arrows.

Figure 8 is an enlarged transverse sectional view of the rotor and cylinder assembly.

Figure 9 is an enlarged elevational view, partly in section, of the rotor, illustrating the arrangement of the lubricating means.

Figure 10 is a fragmentary sectional view, on an enlarged scale, illustrating a modified form of rotor vane or blade.

Figure 11 is a fragmentary perspective view, partly broken away, looking at the exhaust side of the rotary compressor embodying the invention.

Figure 12 is a perspective view of one of the vanes or blades of the rotor, partly broken away, showing the rockable bearing blocks attached to its opposite ends.

Figure 13 is a perspective view of a portion of the cylindrical member of the compressor, showing the arrangement of the slots or ports therein; and

Figure 14 is a side elevational view of an internal combustion engine, shown diagrammatically, and illustrating the application thereto of one of the rotary compressors, blowers, or superchargers embodying the invention.

Referring now to the drawings, the improved rotary compressor, blower or supercharger of my invention is shown as a whole at 15 and comprises a housing or casing composed of an intake section or portion 16 and an outlet or exhaust section or portion 17. The two sections are secured together by a plurality of bolts and nuts 18. A longitudinally extending drive shaft 19 is located within the housing and is journaled at one end in bearings 20 and at its opposite end in bearings 21. The end of the shaft 19 shown at the left of Figure 1 carries a gear 22 which is keyed to the shaft. This gear is in mesh with an internally toothed gear 23 mounted upon a shaft 24 journaled in bearings 25 provided in the hub portion 26 of the housing end. The use of the internally toothed driving gear 23 is important since by using such a driving gear, which follows the pitch of the internal or driven gear 22, which latter is always in mesh with the driving gear 23, the cylinder and rotor can be turned through 180 degrees to permit the rotor to be driven in the opposite direction. The shaft 24 extends through a closure plate 27 and an oil seal or packing 27a which is carried by the plate. The plate is secured to the hub 26 by means of bolts 28. The shaft 24 is drivingly connected with a drive shaft 30 from a power plant, such as a two-cycle or four-cycle internal combustion engine shown diagrammatically at 31, by means of a coupling 29.

The driven shaft 19, it is to be noted, is eccentrically mounted in hangers located within the housing and carries a rotor 33. This rotor is provided with a plurality of radially extending pockets or slots 34 each of which is provided with a lining formed from some suitable self-lubricating material such as sintered brass or bronze 35. The linings could be welded, brazed or bolted to the rotor or the rotor itself could be made of sintered bronze in which case no linings would be required. Located within each of the lined pockets and capable of sliding movement therein is a blade or vane 36 having a straight outer or free edge 36a. The opposite end edges of the blade 36 are notched out at 37 to receive and support substantially cylindrical members or pins 38 which are secured to the blade by rivets or the like 39. Each of these members 38 carries a rockable block or contact member 40 provided with a socket or recess which has a relatively snug fit with the member 38 yet which has sufficient freedom of movement to allow it to be oscillated or rocked relative to the member 38. The part 40 is preferably formed from material similar to the lining material 35 such, for example, as sintered brass or bronze.

It will be understood that as the rotor 33 revolves and as the successive vanes 36 are moved into their respective sockets or pockets 34, in which position they are shown at the bottom of Fig. 2 and at the top of Fig. 3, the contact blocks 40 carried at the ends of the vanes move into their respective recesses 40a, see particularly Figs. 8 and 11.

Mounted concentrically within the housing or casing 15, is a cylinder or cylindrical member 42 provided with a plurality of longitudinally and circumferentially spaced slots or ports to be described hereinafter. This cylinder is, as shown,

provided at opposite ends with flanges which engage and are supported by so-called cylinder carriers or members 43 to which the cylinder is secured by means of bolts 44. The hangers 43 are supported by the outer housing in bearings 16a and 17a, respectively. Annular internal flanges on the hanger members 43 support, at the right-hand end of Figure 1, a bearing assembly 45 and at the left end, a bearing assembly 45a. These bearing assemblies 45 and 45a support a pair of similar guide rings 46 having inwardly directed annular flanges with which the outer surfaces of the bearing blocks 40 are in contact. It is to be noted, see particularly Figure 8 of the drawings, that the outer or free edges 36a of the vanes are located in proximity to the inner surface or wall of the cylinder 42 but are maintained out of contact therewith by virtue of the provision of the rings 46 and the contact blocks 40. Rings 46 are free to rotate on bearings 45 and 45a. Rings 46 are driven by friction from contact blocks. The contact blocks, therefore, do not travel the whole circumference of the rings 46 but only the difference of the length of the arc at the outer and inner position of the contact blocks. Since the contact blocks are mounted for rocking movement relative to their supporting vanes, these blocks will conform to the contour of the inner surface of the rings 46 during rotation of the rotor and vanes. By maintaining the outer edges 36a of the vanes out of actual contact with the cylinder, friction and wear are reduced to a minimum.

Referring particularly to Figure 10 of the drawings, I have shown a somewhat modified form of rotor vane or blade 47. As in the previous form, this vane is provided with notches at its opposite end edges to receive and support a substantially cylindrical member or pin 48 which is adapted to receive and support a contact block or member 49. As in the previous form of invention, the member 49 may be formed from some suitable self-lubricating material such, for example, as sintered brass or bronze. The particular form of blade structure shown in Figure 10 comprises a blade whose outer or free edge between the notched ends thereof is provided with a longitudinal slot or kerf to receive and support a strip or piece 50 of preferably non-metallic material such, for example, as hard rubber, fiber, Bakelite or other suitable material. The strip, as shown, is secured in place by rivets 51. The purpose of providing the strip 50 is to fill the space between the outer edge of the blade or vane 47 and the adjacent wall of the cylinder 42 to thus prevent leakage of the air or other fluid in the compressor. When the parts are assembled the strips 50 have a relatively snug bearing fit with the wall of the cylinder 42 but as the rotor is driven, the strip will wear itself in and thus run free in the cylinder. By virtue of the provision of such a strip it is not necessary to machine the cylinder to a close diameter tolerance, but a close fit will be maintained at all times. Moreover, by employing said strip is not necessary to provide an accurately machined cylinder wall; nor is it necessary that the outer edge of the vane 42 be accurately machined and smooth.

The outer face of each of the cylinder hangers 43 is provided with a segmental stop block 53 which, as shown, is bolted at 53a to the hanger although, if desired, these stop blocks may be formed integral with the hangers. Each of the opposite ends of the housing 15 supports a ring 55 provided with an inwardly extending seg-

mental-like projection 55a. The opposite end edges 55b of the projection are adapted to engage the adjacent end edge of the block 53 as the cylinder 42 rotates a half revolution or approximately 180 degrees. The ring 55 at the right end of Figures 1 or 4 is held in fixed position against the end of the housing by a cover plate 58 and bolts 59. The ring 55 at the left end of the cylinder 42 in Figures 1 and 4 is preferably fastened to the web or partition wall 17a of the housing by bolts or cap screws 60. At this left end there is not provided a cover plate such as plate 58 described above, because of the presence of the shaft end 19 and the gearing 22, 23 at this end of the housing.

The exhaust side or section 17 of the housing is provided with a plurality of longitudinally spaced transversely extending ribs 54. These ribs may be of any desired shape in cross section so long as their inner faces are flat or straight across and the general over-all shape of the rib conforms to the contour of the cylinder 42 with which they are in engagement, see especially Figures 2, 3 and 11. In cases where it is not desirable to compress the fluid before discharge, the ribs can be eliminated.

Referring particularly to Figures 11 and 13, the cylinder 42 is provided with two series of slots or ports 56, 56 in one half thereof and with two series of somewhat longer slots or ports 57, 57 in its other half. It will be seen that the series 56, 56 are staggered with relation to the series 57, 57, i. e., the slots 56 are located at points in the cylindrical member which are between the slots 57. Thus, when the cylinder 42 is in its position of Figures 11 and 13, the series of smaller slots or ports 56 will be behind and thus covered and sealed by the ribs 54, whereas the larger or longer slots or ports 57 will be located between the ribs 54 and thus open or exposed.

In accordance with my invention, the working parts of the compressor which are normally subjected to friction and consequent wear are protected by the application thereto of lubricant in just sufficient quantity to eliminate friction and prevent wear.

The vanes 36 slide in the self-lubricating pocket lining metal 35 and the contact members or blocks 40, also being formed from self-lubricating metal cause only slight wear on the floating rings 46 on which they travel when the compressor is in operation.

The shaft 19 extends throughout the length of the rotor 33 and has adjacent its opposite ends annular recesses or grooves 61 which receive and support annular bands or strips 62 of some suitable packing material, such as felt, which engage the surface of the shaft 19. Shaft 19 is drilled to provide an axial bore or passage 63 through which lubricant may flow and into transversely extending bores or passages 64 and 65 also formed therein. One such passage or bore 64 communicates with a longitudinal pocket or recess 66 formed at the base of each of the pockets 34 formed in the rotor body 33, see particularly Figure 8. The transverse passages 65 feed lubricant to the packing rings 62 which become saturated so that some small quantity of the lubricant is supplied by centrifugal force through passages 67 to the contact blocks 40 to properly lubricate these blocks which are formed from a suitable self-lubricating metal, as previously described. The ball or roller bearing assemblies of the compressor are properly lubricated in more or less conventional manner and thus all working parts

of the apparatus are supplied with the proper quantity of lubricant to provide quiet operation, eliminate friction and to minimize wear on the parts.

Operation

When power is applied to the driven shaft 19 of the compressor C from the drive shaft 30 of the power plant or engine E (Figure 14) through the coupling 29, shaft 24 and gearing 23, 22, the rotor 33 will be driven in a clockwise direction as indicated by the arrows in Figure 2. With the cylinder 42 in the position of Figures 2, 11 and 13, air or other fluid is drawn or sucked in through ports or slots 56 and 57 at the left of Figure 2, compressed by the vanes 36, and discharged through the port or slot 57 at the right of Figure 2 to the internal combustion engine or other power plant E to which it is attached. During this operation, the ports or slots 56 at the right side of cylinder 42 are covered and thus sealed by the ribs 54 and thus permits the air to be compressed until vane 36 reaches the opening 57.

If the engine E should be stopped and then run in the reverse direction, the rotor 33 is caused to rotate in a counterclockwise direction as shown by the arrow in Figure 3. Such reverse rotation of the engine and rotor causes the cylinder 42 with the cylinder carriers 43 which have bearings 20 and 21 eccentrically mounted, to rotate 180 degrees on the bearings 16a and 17a to the position shown in Figure 3 and thus change or reverse the position of the rotor 33, drive shaft 19 and gear 22. The gear 22 at all times engages the internally toothed driving gear 23 and the unit turns until the stop block or segment 53 (see Figure 7) engages the stop or shoulder 55b at the bottom of Figure 7 in which position it remains. As the rotor 33 revolves in a counterclockwise direction air or other fluid is sucked or drawn in through ports or slots 57 and 56 at the left of Figure 3, is compressed by the vanes 36 and discharged through ports or slots 57 at the right of Figure 3. The ports or slots 56 at the right side of the cylinder 42 are closed or sealed by the ribs 54. If now the engine E is again stopped and then run in the opposite direction, the cylinder 42 and rotor 33 will again shift through approximately 180 degrees until the opposite end of the stop block 53 contacts the stop portion or shoulder 55b of the ring 55 at the right of Figure 7 so that the parts again assume their positions as shown in this figure.

It will be understood that by varying the number of vanes 36 of the rotor and the length of the slots or ports 56 and 57 of the cylinder, it is possible to obtain different air pressures from the apparatus.

It is to be understood further that my invention while adapted for use as a rotary compressor or blower, particularly as a scavenging blower for two-cycle internal combustion engines, it is equal-

ly well adapted for use as a supercharger for two-cycle or four-cycle engines, or, with the proper arrangement of the slots 56 and 57, as a rotary pump for liquids, such as oil. In fact, it has many useful and utilitarian purposes which are not mentioned in the foregoing descriptive matter. Moreover, the novel features of my present invention, such as the lubricating features, the use of self-lubricating metal, etc., are equally well adapted for use in connection with a compressor of the vane type which operates in one direction only.

Having thus described my invention, what I claim is:

15. A rotary compressor comprising a housing having intake and exhaust openings formed therein, a drive shaft eccentrically mounted in said housing, a rotor provided with slidable radial vanes keyed to said shaft, a cylindrical member having a plurality of ports formed therein interposed between the housing and rotor and capable of oscillating movement within a limited range, bearings in said housing for supporting the drive shaft, guide rings free to rotate within and located at opposite ends of said sleeve for maintaining the edges of the vanes out of contact with the sleeve, and a plurality of longitudinally spaced transverse ribs located within the housing at one side of said rotor, said ribs providing means for covering certain of said ports when the cylindrical member is in one position relative to the intake and exhaust openings and others of said ports when said member is in another position.
20. In a rotary compressor of the sliding vane type for connection to a source of motive power, the combination of a stationary housing having bearings adjacent the opposite ends thereof and having inlet and outlet openings, a cylindrical sleeve member located within the housing and having end plates mounted in said housing bearings, bearing formed in said end plates, a rotor shaft mounted in the end plate bearings and having a portion extending outwardly beyond one of said bearings, a rotor mounted upon and rotatable with said shaft and provided with a plurality of slidable vanes, said rotor and shaft being eccentrically mounted with relation to said cylindrical sleeve, spaced stops located at opposite ends of said housing, a pinion carried by the extended portion of said rotor shaft, and an internally toothed gear rotatably mounted in an end wall of the housing constantly in mesh with said pinion and operatively connected with the power source whereby to revolve the rotor and vanes in either direction and at predetermined times to shift said cylindrical sleeve member and end plates in opposite directions through approximately 180 degrees between said spaced stops upon the reversal of rotation of said internally toothed gear.
25. A rotary compressor comprising a housing having intake and exhaust openings formed therein, a drive shaft eccentrically mounted in said housing, a rotor provided with slidable radial vanes keyed to said shaft, a cylindrical member having a plurality of ports formed therein interposed between the housing and rotor and capable of oscillating movement within a limited range, bearings in said housing for supporting the drive shaft, guide rings free to rotate within and located at opposite ends of said sleeve for maintaining the edges of the vanes out of contact with the sleeve, and a plurality of longitudinally spaced transverse ribs located within the housing at one side of said rotor, said ribs providing means for covering certain of said ports when the cylindrical member is in one position relative to the intake and exhaust openings and others of said ports when said member is in another position.
30. In a rotary compressor of the sliding vane type for connection to a source of motive power, the combination of a stationary housing having bearings adjacent the opposite ends thereof and having inlet and outlet openings, a cylindrical sleeve member located within the housing and having end plates mounted in said housing bearings, bearing formed in said end plates, a rotor shaft mounted in the end plate bearings and having a portion extending outwardly beyond one of said bearings, a rotor mounted upon and rotatable with said shaft and provided with a plurality of slidable vanes, said rotor and shaft being eccentrically mounted with relation to said cylindrical sleeve, spaced stops located at opposite ends of said housing, a pinion carried by the extended portion of said rotor shaft, and an internally toothed gear rotatably mounted in an end wall of the housing constantly in mesh with said pinion and operatively connected with the power source whereby to revolve the rotor and vanes in either direction and at predetermined times to shift said cylindrical sleeve member and end plates in opposite directions through approximately 180 degrees between said spaced stops upon the reversal of rotation of said internally toothed gear.
35. In a rotary compressor of the sliding vane type for connection to a source of motive power, the combination of a stationary housing having bearings adjacent the opposite ends thereof and having inlet and outlet openings, a cylindrical sleeve member located within the housing and having end plates mounted in said housing bearings, bearing formed in said end plates, a rotor shaft mounted in the end plate bearings and having a portion extending outwardly beyond one of said bearings, a rotor mounted upon and rotatable with said shaft and provided with a plurality of slidable vanes, said rotor and shaft being eccentrically mounted with relation to said cylindrical sleeve, spaced stops located at opposite ends of said housing, a pinion carried by the extended portion of said rotor shaft, and an internally toothed gear rotatably mounted in an end wall of the housing constantly in mesh with said pinion and operatively connected with the power source whereby to revolve the rotor and vanes in either direction and at predetermined times to shift said cylindrical sleeve member and end plates in opposite directions through approximately 180 degrees between said spaced stops upon the reversal of rotation of said internally toothed gear.
40. In a rotary compressor of the sliding vane type for connection to a source of motive power, the combination of a stationary housing having bearings adjacent the opposite ends thereof and having inlet and outlet openings, a cylindrical sleeve member located within the housing and having end plates mounted in said housing bearings, bearing formed in said end plates, a rotor shaft mounted in the end plate bearings and having a portion extending outwardly beyond one of said bearings, a rotor mounted upon and rotatable with said shaft and provided with a plurality of slidable vanes, said rotor and shaft being eccentrically mounted with relation to said cylindrical sleeve, spaced stops located at opposite ends of said housing, a pinion carried by the extended portion of said rotor shaft, and an internally toothed gear rotatably mounted in an end wall of the housing constantly in mesh with said pinion and operatively connected with the power source whereby to revolve the rotor and vanes in either direction and at predetermined times to shift said cylindrical sleeve member and end plates in opposite directions through approximately 180 degrees between said spaced stops upon the reversal of rotation of said internally toothed gear.
45. In a rotary compressor of the sliding vane type for connection to a source of motive power, the combination of a stationary housing having bearings adjacent the opposite ends thereof and having inlet and outlet openings, a cylindrical sleeve member located within the housing and having end plates mounted in said housing bearings, bearing formed in said end plates, a rotor shaft mounted in the end plate bearings and having a portion extending outwardly beyond one of said bearings, a rotor mounted upon and rotatable with said shaft and provided with a plurality of slidable vanes, said rotor and shaft being eccentrically mounted with relation to said cylindrical sleeve, spaced stops located at opposite ends of said housing, a pinion carried by the extended portion of said rotor shaft, and an internally toothed gear rotatably mounted in an end wall of the housing constantly in mesh with said pinion and operatively connected with the power source whereby to revolve the rotor and vanes in either direction and at predetermined times to shift said cylindrical sleeve member and end plates in opposite directions through approximately 180 degrees between said spaced stops upon the reversal of rotation of said internally toothed gear.
50. In a rotary compressor of the sliding vane type for connection to a source of motive power, the combination of a stationary housing having bearings adjacent the opposite ends thereof and having inlet and outlet openings, a cylindrical sleeve member located within the housing and having end plates mounted in said housing bearings, bearing formed in said end plates, a rotor shaft mounted in the end plate bearings and having a portion extending outwardly beyond one of said bearings, a rotor mounted upon and rotatable with said shaft and provided with a plurality of slidable vanes, said rotor and shaft being eccentrically mounted with relation to said cylindrical sleeve, spaced stops located at opposite ends of said housing, a pinion carried by the extended portion of said rotor shaft, and an internally toothed gear rotatably mounted in an end wall of the housing constantly in mesh with said pinion and operatively connected with the power source whereby to revolve the rotor and vanes in either direction and at predetermined times to shift said cylindrical sleeve member and end plates in opposite directions through approximately 180 degrees between said spaced stops upon the reversal of rotation of said internally toothed gear.
55. In a rotary compressor of the sliding vane type for connection to a source of motive power, the combination of a stationary housing having bearings adjacent the opposite ends thereof and having inlet and outlet openings, a cylindrical sleeve member located within the housing and having end plates mounted in said housing bearings, bearing formed in said end plates, a rotor shaft mounted in the end plate bearings and having a portion extending outwardly beyond one of said bearings, a rotor mounted upon and rotatable with said shaft and provided with a plurality of slidable vanes, said rotor and shaft being eccentrically mounted with relation to said cylindrical sleeve, spaced stops located at opposite ends of said housing, a pinion carried by the extended portion of said rotor shaft, and an internally toothed gear rotatably mounted in an end wall of the housing constantly in mesh with said pinion and operatively connected with the power source whereby to revolve the rotor and vanes in either direction and at predetermined times to shift said cylindrical sleeve member and end plates in opposite directions through approximately 180 degrees between said spaced stops upon the reversal of rotation of said internally toothed gear.
60. In a rotary compressor of the sliding vane type for connection to a source of motive power, the combination of a stationary housing having bearings adjacent the opposite ends thereof and having inlet and outlet openings, a cylindrical sleeve member located within the housing and having end plates mounted in said housing bearings, bearing formed in said end plates, a rotor shaft mounted in the end plate bearings and having a portion extending outwardly beyond one of said bearings, a rotor mounted upon and rotatable with said shaft and provided with a plurality of slidable vanes, said rotor and shaft being eccentrically mounted with relation to said cylindrical sleeve, spaced stops located at opposite ends of said housing, a pinion carried by the extended portion of said rotor shaft, and an internally toothed gear rotatably mounted in an end wall of the housing constantly in mesh with said pinion and operatively connected with the power source whereby to revolve the rotor and vanes in either direction and at predetermined times to shift said cylindrical sleeve member and end plates in opposite directions through approximately 180 degrees between said spaced stops upon the reversal of rotation of said internally toothed gear.

ERLING BORSTING.
